19 Claims. (Cl. 105—112)

1

This invention relates to driving mechanisms for car accessories such for example as air circulating fans used to set up air circulation in refrigerator or other railway cars. Such use of the driving mechanism is typical; but the invention may be used for driving any accessory from the running gear.

One of the primary purposes of the invention is the provision of driving mechanism adapted particularly for operation on railway express refrigerator cars, which are operated at high speed and in which the large truck spacing and axle spacing on each truck produce relatively great angular and lateral shiftings between the car body and wheels. Also the relatively soft springs with swing hangers allow greater lateral motion than obtains in standard refrigerator cars.

The present invention provides a drive mechanism particularly adapted for taking its initial drive from a drum mounted on the central part of an axle, where the drum can be wide enough to accommodate the lateral displacements due to both lateral and angular movements between truck and body. But although it is so particularly adapted, the drive mechanism of the invention includes within its capabilities the taking of its initial drive from any suitable element on the wheel and axle unit, e. g. the regular car wheel.

A general introductory description of the preferred characteristics of the invention will help to make the invention understood from the following detailed description of its present preferred form. A drive shaft is located preferably under the car floor and on an axis which extends laterally relative to the car. One end of the shaft is preferably located at or near the plane of the car side wall so that the drive may be taken from that end in the plane of the wall. That arrangement, although convenient for the air-fan type of accessory, is not a restriction on the invention, as other locations of that end of the shaft may be convenient for driving accessories, such as generators, which may be located under the car floor. However, for descriptive convenience, without limitation thereto, that end of the shaft will be referred to as the outer end. The other or inner end of the shaft is located in or near the general plane of the element on the wheel and axle unit from which the initial drive is being taken. Again for descriptive convenience, but without limitation, that element will be referred to as the driving drum.

The shaft is mounted on, or in, a shaft carrier; typically in a shaft carrying tube. The inner end of that tube is mounted for rotation about

2

a longitudinal axis and for swinging motion through at least a small angular range about an axis or axes which is or are transverse of the tube. A traction roller is carried on an arm which extends transversely from the shaft carrier tube. A transmission, preferably of the belt and pulley type, connects the roller rotatively with the inner end of the shaft. Rotational swinging of the carrier about a longitudinal axis throws the traction roller into and out of tractive engagement with the drum.

The outer end of the shaft carrier, or in effect the outer end of the shaft, is so mounted that it may rotate about a longitudinal axis and also that in normal operation it may have a swinging movement, independent of that rotation, toward and from the shaft which is finally to be driven. So far as the invention is concerned that shaft may be the actual accessory shaft or any intermediate driving shaft. In either instance it will be referred to, for descriptive convenience but without limitation, as the accessory shaft.

Movement of the outer end of the shaft toward and from the accessory shaft renders the drive transmission (typically a belt drive) inoperative or operative. When the mechanism is rendered inoperative it is desirable that the traction roller also be moved out of its tractive engagement. It is one of the features of preferred forms of the invention that the independent movements of the outer shaft end that are necessary in normal operation are provided by a simple linkage and pivot unit which acts in such manner that both the required relieving movements are derived from a single, manually caused, movement. That is, while the two movements or freedoms referred to are independent in normal operation, they are caused to depend one upon the other, in the relieving operation.

The linkage and pivot hangar unit just referred to also has distinct advantages of simplicity of manufacture and of requiring no great precision of location on the car body. In fact, one of the advantageous features of the invention, and of its preferred design, lies in its non-restriction of precise mounting and in its flexible ability to accommodate distortions of the car body. Another feature promoting simplicity lies in the use of a single spring to urge the shaft carrier both relatively and swingingly to engage the traction roller with the drum and to keep the final driving belt tight. Other objectives and accomplishments of the invention will appear.

The drawings show the invention, in its pres-

ently preferred form and detailed design, applied to a typical car structure and use, illustratively, for driving a ventilating fan of the type shown in the Van Dorn Patents 2,214,210 and 2,349,315. The showings in the drawings are intended to be merely an illustrative and typical form of the invention; and the fan is illustrative of any car accessory which may be driven by the driving mechanism of the invention.

In the drawings:

Fig. 1 is a fragmentary view, on line 1-1 of Fig. 3, in vertical section transverse of the length of the car;

Fig. 2 is a similar view on the same sectional line, Figs. 1 and 2 together comprising a complete transverse vertical section which may be composed by placing Fig. 2 to the right of Fig. 1 with the two axial lines A in alinement;

Fig. 3 is a view showing the mechanism in normal operative condition, essentially in side elevation, as indicated by line 3-3 on Fig. 1, but with the lower part of the view taken on line 3-3 of Fig. 2;

Fig. 3a is a detail section on line 3a-3a of Fig. 4;

Fig. 4 is a view similar to Fig. 3 showing positions of the parts different from Fig. 3 and with the upper part of the figure taken in sectional elevation as indicated by line 4-4 on Fig. 1, and with certain parts broken away to show parts behind;

Fig. 5 is a sectional elevation on line 5-5 of Fig. 2;

Fig. 6 is a fragmentary plan section on lines 6-6 of Figs. 1, 2 and 3 with some parts broken away;

Figs. 7, 8, 9, and 10 are explanatory diagrams; and

Fig. 11 is a view of a modified form.

Fig. 12 is a diagram showing a modification.

Figs. 1, 2, 5 and 6 are all to the same scale. Figs. 3 and 4 are on a reduced scale.

In the drawings various parts of a typical car structure are shown in various aspects. In Fig. 1 a fragment of the lower part of the car side wall is indicated generally by the numeral 10, that part of the side wall being also seen in exterior elevation in Fig. 3 and in elevational section in Fig. 4. In Fig. 1 a fragment of a typical floor structure is shown as comprising the upper flooring 11 and the lower floor structure member 12. In Fig. 2 the lower floor member 12 is shown in its continuation to the right of the parts shown in Fig. 1. Fig. 5 also shows the lower member of the floor structure; and Figs. 3 and 4 indicate in broken lines the relative locations of the floor structure members 11 and 12. The composite floor structure is merely typical and will be referred to simply as the floor or floor structure. The casing of a typical ventilator fan is shown at 15, in Figs. 1, 3 and 4, in its typical position on and over the floor. The driving shaft 16 of this typical fan is shown as projecting out through side wall 10, or at least partially through the thickness of the wall into an external wall recess which is covered by a cover plate 20 (or the external wall sheathing) at the external surface of the wall. The structure and the casing of this recess in the wall is of no particular significance to this invention.

Sheave 22 is carried by shaft 16 in the recess which also accommodates driving belt 24 that drives sheave 22 from a sheave 26 which is mounted on the outer end of driving shaft 28. Driving shaft 28 is journaled in a shaft-carry-

ing tube 30 which extends laterally and substantially horizontally under the car floor. Bearings for shaft 28 in tube 30 are indicated at 28a (Fig. 6). The inner end of shaft 28 is driven, as will be described, from a wheel (32) and axle (34) unit of the car, and the outer end of shaft 28 carries the sheave 26, in the vertical plane of upper sheave 22, in a position below the car floor. Driving belt 24 is kept tractively tight, or is released to non-tractive looseness, by movement of the outer end of carrier tube 30 and shaft 28 in directions which may be preliminarily described as generally up and down (to and from accessory shaft 16). With driving belt 24 in its tractive condition, fan 15 or any other car accessory is driven from the wheel and axle unit. With belt 24 released, the accessory may be independently driven from a suitable independent source of power through the belt indicated at 36, and the sheave 38 which may be temporarily attached to the permanent sheave 22. Belt guards 21 and 25 prevent the belt from entirely leaving the pulleys 22 and 26 when 26 is lifted. Guard 25 is mounted on carrier tube 30 by bracket 27.

The inner end of shaft carrier tube 30 is mounted on the car body, preferably in the manner here described, for rotation about an axis longitudinal of itself and for swinging movements about an axis transverse of its longitudinal axis. As will become evident, it is immaterial whether the longitudinal rotation axis of the carrier tube is co-axial with the tube or somewhat offset from the tube axis. Because of simplicity, and particularly to allow the desired freedom of movement of the outer end of the tube in a simple manner, the inner end is mounted to swing in both degrees of freedom about an effective point of support non-axial of the tube. (See Figs. 5 and 6.) As illustrated, a bracket 40 is mounted on the undercar framing 42 and carries a pivot pin 44. Tube 30 carries near its inner end a projecting apertured lug 46 which fits loosely over pivot pin 44 to permit the tube to swing through the required small angle about a transverse axis. Or, to allow the necessary freedom without looseness, the lug may be provided with a rubber bushing fitting the pin snugly. Such bushings are described below in similar situations. They have the effect of eliminating wear and rattling which may be caused by loose movements of the parts. In any event, whether the rubber bushing is used or not, the support of the tube on pin 44 is in full effect a point support which allows the tube to rotate and/or swing, through the necessary operating angles, about both longitudinal and transverse axes.

Sheave 50 is mounted on the inner end of shaft 28 where the shaft projects beyond the inner end of carrier tube 30. A guard 52 is mounted, by bracket 54, on tube 30, to overhang belt 56 and pulley 50; to prevent the belt from being easily removed. Belt 56 is driven from a lower sheave 58 (see Fig. 5) which is mounted on shaft 60 of a traction roller 62. The traction roller is adapted normally to engage the surface of drum 64 mounted on car axle 34, preferably centrally between its two car wheels. Driving sheave 58 and traction roller 62 are carried by the inner end of carrier tube 30 in the preferred manner now described.

A hanger arm 70 extends in a generally radial direction and generally downwardly from the inner end of carrier tube 30. At its lower end

arm 70 carries a stud shaft 72 on a horizontal axis, and a hub 74 of a vertically swinging arm 76 is swingingly mounted on stud shaft 72. Arm 76 projects in a general horizontal direction from stud 72 toward traction drum 64. At its outer swinging end arm 76 carries a journal hub 78 in which the shaft 60 of traction roller 62 and lower driving sheave 58 is journaled on a horizontal axis. A compression spring 80 is mounted around a vertical rod 82 which is mounted on hanger arm 70, the upper end of the spring bearing against a collar 84 fixed on the rod, and the lower end of the spring pressing downwardly on swinging arm 76. The lower end of rod 82 passes loosely through a hole in arm 76. The action of spring 80 is to keep driving belt 56 in tractive tight engagement with sheaves 50 and 58.

As will be apparent from what has been described so far, traction roller 62 will be swung toward the left in Figs. 3, 4 and 5, and into tractive engagement with drum 64, when the inner end of carrier tube 30 is rotated or swung in a clockwise direction about its pivotal point of support. And rotation of the inner end of the tube in the opposite direction will swing traction roller 62 away from contact with drum 64, to such a typical position as is illustrated in Fig. 4.

The outer end of carrier tube 30 is mounted so that it can rotate with the inner end of the tube and also swing or translate in a direction which is generally toward and from the upper accessory shaft 16 and its sheave 22. The preferred mounting includes a mounting arm 90 rigidly secured at one end to tube 30 and normally extending transversely of the tube in a generally horizontal direction, toward the left in the aspect of Figs. 3 and 4. The outer end of arm 90 carries a projecting transverse pin 92 (see Figs. 1 and 6) which underlies a suitable downwardly facing surface that limits the upward movement of that end of the arm while allowing it freedom to move down and to move horizontally to right and left in Figs. 3 and 4. The lower flange 94 of car side-sill 96 conveniently provides that downwardly facing surface.

At a medial point in its length, preferably closer to tube 30 than to pin 92, arm 90 rigidly carries a pivot stud 98 extending from the arm parallel to the axis of tube 30. The projecting end of stud 98 is flexibly carried in rubber bushing 101 in the end 100 of a swinging arm or link 102 whose pivoted end 104 is swingingly mounted on a horizontal transverse stud 106 which is conveniently mounted on side sill 96. The hub end 108 of a manipulating arm 109 is also conveniently mounted to swing (independently of arm 102) on stud 106. Arm 102 extends from pivot stud 106 in a direction which is transverse of the line between accessory shaft 16 and driving shaft 28 so that the swinging movement of the outer end 100 of the arm, and of stud 98, will be generally along a line so directed that the movement (carrying tube 30 and drive shaft 28 with it) will loosen or tighten belt 24. (See Figs. 3 and 4). As will be understood from the succeeding description of operation, it is only the translational component of the movement of stud 98 in the direction established by the spatial relationship of shafts 16 and 28 that is utilized in tightening and freeing the belt. Accordingly, stud 98 as a carrier for the outer end of tube 30 and shaft 28, or the tube-shaft unit itself, might be mounted to slide translationally along a line of movement parallel to the line between shafts

16 and 28, or with a component along that line. However, the mounting using a swinging arm such as 102 is more simple and accordingly preferred.

Spring means are provided for rotatively urging carrier tube clockwise in the aspect of Figs. 3, 4 and 5, thereby to swing carrier arm 70 toward the left and move traction roller 62 against drum 64, and also for urging the outer end of the carrier tube and sheave 26 downwardly, away from sheave 22, to keep belt 24 taut. Although two independent springs (or weights) could be used for those functions, the single torsion spring element shown in the drawings is preferred.

As seen best in Figs. 1, 2 and 6, the spring element is in the form of a torsion rod having a medial straight portion 110 with a transversely extending arm 112 (Fig. 5) at one end and another transverse arm 114 at the other end. Straight portion 110, near the outer transverse arm 114, is loosely confined in a lug 116 which is rigidly mounted on the outer end portion of sleeve 30. In practice the lug is made in the form of a clamp as shown, and a rubber bushing 118 directly surrounds the rod to eliminate any rattle-producing looseness; but the functional effect is the same as if rod 110 simply passed loosely through lug 116. The straight torsional portion 110 of the spring is substantially parallel to tube 30.

At its inner end the spring is secured to carrier tube 30 in such a manner that the torsional reaction of the spring, producing a torque about the axis of spring section 110, is transferred to the carrier tube. In the present preferred modification such a connection is made by confining spring arm 112 in a channel member 120, which is rigidly connected between tube 30 and hanger arm 70 and thus serves also as a brace for the hanger arm. The extreme end 122 of arm 112 is bent at an angle to 112 and projects through an opening 124 in the channel bottom, preventing 112 from being displaced along the length of the channel more than the looseness of 122 in 124 permits. A pin 126 confines spring arm 112 in channel 120 and prevents or limits movement of the whole spring unit lengthwise of central portion 110. The outer end of outer spring arm 114 is confined by bearing upwardly into a notch 128 in a lug 130 welded to the car frame, for instance to the underside of side sill 96. See Figs. 3 and 3a.

The spring is torsionally loaded so that, in the relative positions of its arms shown in Figs. 3, 4 and 5, arm 112 is urged clockwise and arm 114 counter-clockwise. The outer end of arm 114 presses up into the notch 128. Spring torque is transmitted through arm 112 to urge tube 30 and the hanger arm 70 clockwise to press traction roller 62 against the drum. In reaction to those pressures, there is a pressure by the spring in a general downward direction on the lug 116 by which the outer part of spring portion 110 is connected to the outer end portion of carrier tube 30. The magnitudes of the spring exerted forces depend generally on the loading of the spring; their relative magnitudes depend on such factors of spring design as the effective length of spring arm 114 and the relative direction of the pressure axis at the point where spring arm 114 engages lug 130. The relative spring dimensions and dispositions shown in the drawings are suitable, with proper loading, to maintain the traction roller in effective drum contact and at the same time to press sheave 26 downwardly with

a force suitable to maintain proper tension on belt 24.

The action of the spring on the carrier tube is the same as if the spring were substituted by a rigid arm rigidly attached to the outer end part of the tube, in the general relative position of spring arm 114, and with a spring exerting a generally downward thrust on the outer end of that arm. The torque tending to rotate the tube about its longitudinal axis then depends, as it does in the described spring arrangement, with any given spring pressure, on the effective radial length of the arm and the direction of spring pressure. And, with any given spring thrust at the end of an arm of given length, the magnitude of the thrust component which urges the shaft carrier along its guided line of movement away from accessory shaft 16, depends then on the direction of the spring force applied to the outer end of the arm. By disposing that direction at an angle to the direction of carrier movement, the effective component is a maximum when that angle is zero, and becomes less as that angle approaches 90°. In the design shown in the drawings, utilizing the illustrated spring, the same thing is accomplished by the simple expedient of bending the outer end 114a of spring arm 114 so that the axis of its pressure engagement with lug 130 is at an angle to the guided direction of carrier movement.

The effective torque about the axis of tube 30, tending to press roller 62 against drum 64, depends also upon the direction of the spring force, since only the component of that force which is normal to the lever arm is effective in producing torque. The lever arm is substantially the radial line from the tube axis A to the point of spring application (in the present instance the point of contact of spring arm 114 and lug 130). The torque produced by a given spring force also depends upon the length of that lever arm. By suitable choice of the lever arm and the direction of the spring force both with respect to the lever arm and with respect to the axis of belt 24, it is thus possible to control the relation between the tension of belt 24 and the tractive pressure of roller 62 on drum 64.

In practice, the distribution of the spring forces is preferably made such that the outer driving belt 24 will slip before traction roller 62 will slip on the drum, in the event of the accessory being overloaded or jammed. The independent spring force applied to inner belt 56 may also be such that belt 24 will slip before belt 56, if so desired. The worn belt is much cheaper and easier to replace than a worn traction roller; and of the two belts, 24 is easier to replace. It has been said that individual springs, or weights, can be used to urge the shaft carrier in its two movements of rotation and translation. A spring or springs are preferred, particularly for the rotational movement that keeps roller 62 in tractive engagement with the drum, as the spring does not add inertia to the parts which are in constant drum-following movement. Weight could be substituted for the spring action which presses the outer end of the shaft carrier away from the accessory shaft; but even there spring action is preferred. It should be noted, however, that in the arrangement shown in the drawings where the outer end of the carrier moves in a general downward direction to tense belt 24, a part of the belt tensing force is supplied by the weight of the carrier and its carried and attached parts.

Fig. 3 shows the various parts in their normal

operating positions with traction roller against drum 64 and with belt 24 taut. In that condition the position of the outer end of drive shaft 28 and the axis of the outer end of tube 30 is fixed by several inter-related factors. As is evident from Fig. 3, clockwise rotation of the outer end of carrier tube 30 and its attached arm 90 about the tube axis is limited by contact of traction roller 62 with drum 64. Assuming for the moment any given position of the running gear drum with relation to the car body, the rotational position of tube 30 and its attached parts is fixed. In normal operating condition, the torsion spring presses shaft 28 and sheave 26 away from sheave 22. Due to belt 24 which determines the distance of shaft 28 from shaft 16, the outer end of shaft 28 and of tube 30 are thus restricted to swinging movement about shaft 16 at the established radial distance. That swinging movement is prevented by the linkage formed by link 102 between fixed pivot 106 and the pivot stud 98 on sleeve-fixed arm 90. (It will now be seen that the pivotal connection at 98 could be concentric with tube 30; and the same is true of the pivotal mounting 44 at the inner end of the tube. And those two pivotal mountings do not have to be co-axial, seeing the looseness at 44 and at 100.) For its function of preventing the stated swinging movement, the relative direction in which link 102 extends is not at all critical. It is only necessary that the link extend transversely of a line between 30 and 16. In practice it is desirable that the link extend at a fairly large angle to the line determined by 16 and 28 so that substantial changes of belt length, and also that the following described action of disabling the drive mechanism, can both be readily accommodated.

In normal operating conditions, the inner end of tube 30 rotates on a longitudinal axis about stud 44 as traction roller 62 swings to the left and right in Fig. 3 following the relative movements of drum 64. The necessarily accompanying rotation of the outer end of tube 30 may be considered as a rotation of that end of the tube about its own axis, although it can be viewed as a rotation about the (then slightly moving) stud 98. As the inner end of the tube rotates for instance clockwise to keep roller 62 against the drum, corresponding rotation of the outer end of the tube and of arm 90 swings the left hand end of the arm up. That angular movement of arm 90 moves stud 98, and the swinging end of link 102, upward; correspondingly straightening out the angle between arm 90 and link 102 and moving the outer end of tube 30 slightly to the right along an arc centered at shaft 16. The normal spacing of stud 92 below surface 94 allows of the necessary angular movement of arm 90 and the accompanying upward movement of the stud. On opposite, counter-clockwise, rotation of tube 30 to accommodate drum movement to the right, opposite angular changes in the relations of 90 and 102 take place. During all these drum-following actions, rotation of the tube and its attached parts may therefore be viewed either as rotation about either the line A₂ or the line A₃ shown on Fig. 6; in either case as rotation about a longitudinal axis.

The manual lever 109, freely pivoted to the car frame conveniently at stud pivot 106, normally hangs in the position shown in Figs. 1 and 3, where it rests on a support 140 which projects inwardly from a casing 142 that is mounted

under side sill 96 to cover the mechanism. In that position the part 109a of the arm is spaced from stud 98. When the arm is swung up toward the position of Fig. 4 it moves up to the right against stud 98 and raises that stud in a swinging movement about pivot stud 106. During the first part of this part of the action the arm 90 does not swing about the axis of either stud 98 or shaft 28 as traction roller 62 is still held against drum 64 by the spring action. Arm 90 and the outer end of tube 30 are simply swung in what may be regarded (in the aspect of Figs. 3 and 4) as substantially a translation about pivot 106 (see below). The same thing would occur if stud 98 were concentric with tube 30 and/or if lever 109 lifted directly on tube 30. Seeing that the translation direction has a substantial component in the direction of the line 16-28, the belt 24 is loosened.

During that substantially translational upward movement of the outer end of tube 30 and its attached parts, the whole tube assembly is in fact swinging about a transverse axis through mounting lug 46. The line B₁ in Fig. 6 represents the location of that axis in plan; or represents the vertical plane in which that axis lies. The orientation of that axis, as viewed in elevation, is shown by the line B₂ in Fig. 3; being determined by the orientation of arm 102 and changing somewhat as that arm swings up as described just above.

Pin 92, on the end of arm 90, normally lies in a position spaced below lower sill flange 94. It contacts the flange after an amount of upward translative movement which is determined by that normal spacing. With pin 92 prevented from moving up from its stopped position (see Fig. 4) further upward movement of stud 98 and tube 30 causes a counter-clockwise rotation of that end of the tube about the upwardly moving pivot stud 98. Consequently the tube as a whole rotates counter-clockwise about the longitudinal axial line A₃ of Fig. 6, and the parts thus reach the position shown in Fig. 4 with traction roller 62 swung away from drum 64 and with pulley 26 raised toward pulley 22, with belt 24 loose. To hold the parts in those positions, lever 109 is hooked over a suitable projection, such as the one shown at 150 in Fig. 3a, projecting from the inner lower edge of casting 142.

From the foregoing it will be seen that the movements of shaft carrier tube 30 (of the journals in which the shaft is carried) can be described briefly as a swinging movement about the transverse axis B₁, B₂ (Figs. 6 and 3) and a rotational movement about the longitudinal axis A₃ (Fig. 6). Due to the fact that link 102 swings through an appreciable angle, the orientation of the transverse axis (as seen in Fig. 3) shifts somewhat in operation; but that orientation shift may be minimized by making link 102 longer, or entirely eliminated by guiding the outer end of the shaft rectilinearly as has been noted. In any event the swinging movement of the shaft is one that takes place about a determined transverse axis. And with regard to the longitudinal axis of carrier or journal rotation, it is noted that the functional effect is the same whether the rotation is about the carrier axis or about an offset axis such as A₃ substantially parallel to the carrier axis.

Certain typical modifications and adaptations are schematically illustrated in Figs. 7 and following, in which the diagrammatically represented parts are, with exception of those particu-

larly referred to, given the same identification numerals as before. In Fig. 7, link 102a is shown as extending between fixed pivot 106 and the axis of tube 30. And the action will be described as if the inner end of tube 30 (its far end as seen in the figure) were mounted to rotate and to gyrate about an axial point on its own axis.

When the outer end of the axis of tube 30 swings up about center 106 to the tube position

- 10 shown at 30a, arm 90 and pin 92 move up in translation to the position where pin 92 is at 92a in contact with 94. Tube 30 has not rotated about its axis to any substantial degree, due to the fact that roller 62 on arm 70 at the inner end of the tube is still held in contact with drum 64 by the spring. On further lifting of 30 to 30b, the outer end of 30, together with arm 90, swings about 92 as a pivot; which pivot may slide from 92a to 92b. Hanger arm 70 is thus swung to 70a through 15 an angle about the inner-end pivot of 30 that is equal to the angle between the two positions 90a and 90b of arm 90. If 92 slides in this last part of the movement, it is only necessary that the guide surface (as 94) be transverse of the path 20 of movement of 30.

It will be understood from the described operation of the preferred form of the invention and particularly from the immediately preceding discussion of the modification shown schematically in Fig. 7, that the swinging end of link 102a is not necessarily pivoted on the rigid structural unit which includes tube 30. It may be for example, pivoted directly and axially upon driving shaft 28. Link 102a then in full effect provides a 30 journal for the outer end of that shaft, that journal and the shaft being movable (by swinging of the link about its fixed pivot 106) along the axis of belt 24. With the swinging end of the guiding link 102 thus connected directly to the shaft, 35 rather than to it through the shaft carrier, the journaling of the shaft in the carrier then performs the primary function of keeping the shaft and carrier in axial alignment. The spring means by which the outer end of shaft 28 is urged downward to tighten belt 24 can then be connected 40 either to tube 30 as before or to the swinging end of link 102a, or, indeed, in any manner by which transverse translational force can be transmitted to the shaft.

- 50 Similarly the transmission disabling motion of the outer end of shaft 28, indicated by the arrow in Fig. 7, can be produced by a lifting force applied to the system at any one of many points, including, for example, the outer portion of tube 55 30, the link 102a (at a point not too near pivot 106), arm 90 (at a point not too near pivot 92), or even shaft 28 itself, since that shaft is idle when the disabling device is used. On the other hand, the pivot stop 92 (the function of which 60 is to cooperate with the lifting force to exert a torque upon carrier 30 by which roller 62 is lifted off drum 64) must be associated with carrier 30 and not merely with shaft 28. Thus pivot 92 is preferably mounted, as in the preferred modification, in fixed relationship to carrier tube 30, and at a point longitudinally spaced along the tube from its inboard support (44). (In this connection, compare Fig. 10, described below.)

- An illustrative embodiment of the invention, 70 modified along the lines just described, is represented in Fig. 11. That figure corresponds in aspect to Fig. 6, but for clarity does not repeat that portion of Fig. 6 lying to the right of the vertical break, since all of the mechanism there shown can be (although it is not necessarily) the

11

same in the modified and the preferred embodiments. In Fig. 11 a journal for the outer end of shaft 28 is provided by the sleeve 160, which is quite independent of carrier tube 30f. Sleeve 160 is mounted directly, and in the present instance rigidly on the swinging end of link 102f, which corresponds functionally to link 102 of the preferred form. Link 102f is pivoted at its other end 104f on fixed pivot 106f, the pivot bearing being so-constructed as to allow some freedom of movement about an axis transverse to the pivot axis (corresponding to the freedom provided at 101 in the preferred form). As illustrated, a thick rubber bushing 165 is provided between link end 104f and the sleeve 166 which forms the actual pivot bearing. The outer end of shaft 28 is thus capable of swinging movement about pivot axis 106f, that movement having a component along the axis of belt drive 24, as in Fig. 7. Such swinging movement of shaft 28 is urged by spring 110f in a direction to tighten belt 24 and render the drive operative. Spring 110f is shown connected via bracket 116f to journal sleeve 160, rather than to carrier tube 30 as in the preferred form. Either type of connection transmits the required translational force to shaft 28 to tighten belt 24.

Manual means for lifting shaft 28, in opposition to the spring force, are provided as before by a hand lever 109f, which is pivoted (as before) on fixed pivot 106f, but which in the present modification exerts its lifting force directly on journal sleeve 160, rather than on a pivot stud 98 as in the preferred form.

Arm 90f is mounted rigidly on the outer end of carrier tube 30f and carries pivot stop 92f in a position to engage the under surface of flange 94 as shaft 28 is swung upward, as in Fig. 7. Stop 92f then functions like stop 92 in the preferred form to rotate the carrier tube about a longitudinal axis with continued upward swinging of shaft 28, moving drive roller 62 from drum 64. However, in the present embodiment, the means for controlling the swinging motion of shaft 28 (including journal sleeve 160, pivoted link 102f, spring connection 116f and lift lever 109f) are structurally independent of the means for translating that swinging motion (within a predetermined portion of its range) into rotational motion of carrier tube 30f (including arm 90f, pivot stop 92f and transverse stop engaging surface 94). Consequently, it is not necessary in this modified form to provide, for the outer end of the shaft carrier, a direct mounting on the car body such that the carrier may rotate about an axis longitudinal of the shaft and also translate to and from the accessory shaft. In full effect however those mounting freedoms are provided indirectly. The carrier (which may here be considered as a shaft carrying journal for the inner end of the shaft) can and does rotate about the shaft axis when the traction roller is following the drum in normal operation. It is translationally mounted, indirectly, on the swinging arm 102f via the shaft on which both the carrier 30f and arm 102f are journaled. And, when the outer end of the shaft is lifted to make pin 92f effective as a pivot, the whole carrier assembly then rotatively swings about an axis passing through 92f and pin 44, just as in the preferred form.

Fig. 12 is a schematic diagram, corresponding to the central portion of Fig. 7, and illustrating a modification which will be described initially as a modified form of Fig. 11. For that purpose the arm 90g in Fig. 12 is to be considered as rigidly mounted on carrier tube 30f, which lies di-

rectly behind journal sleeve 160 as seen in the diagram. Arm 90g carries a stop element 92g, which corresponds to stop pivot 92 in Fig. 7 and to stop pivot 92f in Fig. 11, but is adapted, upon upward swinging of the forward end of shaft 28 about pivot 106f, to contact the under surface of link 102f rather than a fixed surface such as 94. Such contact is indicated at 92h. Upon further upward swinging of shaft 28, arm 90g is caused to swing with link 102f about pivot 106f, just as if (in the present illustrative embodiment) it were rigidly connected to that link. Thus carrier tube 30f and arm 70 are rotated about a longitudinal axis through pivot 106f and inner support 44 of the carrier, bringing arm 70 into a position 70b in which the drive from drum 64 is disabled.

It may be noted that the effect of stop 92g is to make link 102f effectively a rigid part of unit 30, 90g, which then rotates as a whole about pivot 106f. The stop surface itself does not become a pivot, as in the preferred form. A useful way of viewing the modification of Fig. 12 is to consider that the two functions of stop 92 of the preferred form (acting as a simple stop and forming a pivot) are shared in Fig. 12 between stop 92g, which performs the stop function, and pivot 106f, which performs the pivot function.

It will be understood that such an arrangement, in which the stop element (92) engages a suitable moving part of the mechanism rather than a fixed surface, can be used also in connection with the embodiment of Fig. 7 (in which link 102a is pivoted on carrier 30). Similarly, in the preferred form of the invention (Figs. 2 and 3, for example), arm 90 can be so formed that stop 92 engages link 102, the effect then being to disable pivot 98 and make link 102 temporarily an effectively rigid part of the unit 30, 90.

The general arrangements so far shown and described have been designed for suitability to drive an accessory shaft (such as 16) situated above a driving shaft that is located below the car floor; and for tractively contacting the side of an axle drum located at a level below the driving shaft. Simple re-arrangements of the relative positions of parts will adapt the mechanism to engage the top of an axle drum or car wheel, and to drive an accessory shaft which may also be located below the car floor.

Fig. 8 shows schematically how the mechanism may be rearranged to make traction roller 62c engage the top rather than the side of drum 64c; and how sliding movement of 92 from its position where it strikes 94 may be obviated. It may be remarked that if pivot point 106 be made coaxial with position 92c, then 92 will not slide on 94 during the last part of the swinging movement. In that arrangement 92 needs no sliding surface; any sort of stop to limit it to position 92c will suffice.

In Fig. 8 the fixed pivot of link 102c is shown at 106c coincident with 92c. In the first part of the movement, the axis of 30 swings about 106c and 90 and 92 move up in translation about pivot 106c, roller 62c remaining in contact with 64c. In further upward movement of 30, the whole system at the outer end of 30 swings about the common fixed axis of 92c and 106c, and hanger arm 10c and roller 62c at the inner end of 30 swing up through a commensurate angle. The action of arm 10c and roller 62c is the same as before, with reference to 64c, although here the arm is shown as projecting substantially horizontally from 30.

Fig. 9 schematically shows simple re-arrangements for driving an accessory shaft 16d which may be located below the car floor.

Hanger arm 70, roller 62 and drum 64 are shown in the same relation to 30 as in Fig. 7; although they can be in any other suitable relation, e. g. that of Fig. 8. Accessory shaft 16d is shown at about the same level as 30, instead of above it. Link 102d is shown as pivoted at 106d in a position where the link extends transversely of a line between 30 and 16d. As in Fig. 8, 106d might be coincident with position 92e at which the movement of pin 92d on arm 90d is stopped by stop surface 94d. If 92d slides, as it will here, surface 94d need only be transverse of the swinging movement of 30 about pivot 106d. Thus it is here shown as vertical. The movements, with relation to shaft 16d and drum 64, are the same as in Fig. 7; assuming that the outer end of 30 is forced toward the right and that the spring acts against counter-clockwise rotation of 30 and presses its outer end toward the left away from 16d.

It has been remarked that pivot 106 may be in any position in which link 102 extends transversely of a line between 30 and 16. Thus, 106 might be below 30 in Fig. 9; or to the right of 30 in the other figures; with the same resulting movements of the parts.

The position of pivot pin 92 with relation to the disposition of the other parts is governed by similar considerations. The pivotal position of 92 (e. g. 92a in Fig. 7, or 92e in Fig. 9) need only have such relation to 30 that swinging of 30 about that pivotal position has a component in the direction of a line between 30 and 16. That is, arm 90 extends transversely of that line. Whether it extends to the left or right of that line in Fig. 7, or above or below that line in Fig. 9, depends on the direction in which roller 62 moves to engage drum 64. For instance in Fig. 7 if drum 64 were to the right of 62 (see 64f) so that arm 70 would swing to the left to move away from the drum, that swinging movement would be accomplished by having 90 extend to the right of 30, with pivot pin 92 to the right of 30. In such a re-arrangement of the parts the spring would be applied to press the outer end of 30 down (away from 16) and to oppose clockwise rotation of 30.

In the forms so far described, the action of relieving the belt precedes the action of swinging the traction roller away from the drum, the latter only taking place when shaft 28 has been moved toward shaft 16 through the distance measured by the normal spacing of pin 92 from its associated stop surface. The reason for that sequence is the relative location of the point at which the pressure is applied (by lever 109 or equivalent) on the shaft carrier organization to move it. That point of application is such that the moment set up by the spring forces which urge the carrier rotatively and hold roller 62 against the drum, are not overbalanced until pin 92 strikes its stop surface to form a (till then, non-existent) pivot about which the applied force then sets up a rotative moment. In Figs. 7, 8 and 9, for instance, the applied relieving force is assumed to be applied, in effect, to the axis of tube 30 at its outer end. That force so applied does not at all alter the rotative moment equilibrium of the tube, with roller 62 against the drum. Consequently the carrier tube does not rotate until 92 strikes 94. The same general considerations apply in Figs. 3 and 4 where the relieving

force is applied to the stud 98 on which the carrier is pivoted to guiding arm or link 102.

Fig. 10 shows an arrangement in which, among other things, the sequence of relieving actions is modified. In this figure the carrier tube 30, its shaft 28, accessory shaft 16, hanger arm 70, roller 62 and drum 64 are shown as in Figs. 3 and 4 and Fig. 7. Arm 90e is here shown as projecting relatively oppositely from tube 30 (as has been mentioned before). Guiding link 102 may here be connected as, e. g., in Fig. 7; but to show that the link may be connected at any point to the outer end organization of the carrier, link 102e is here shown as extending between a fixed pivot 106e and a pivotal connection to the outer end of arm 90e.

Spring 200 (typifying any yielding force) is shown pressing down on the outer end of arm 90e; that spring setting up a moment which rotates carrier 30 (assumed to be loosely rotatively pivoted at its inner end as before described) to press roller 62 against the drum and also exerting a downward pressure on the outer end of the carrier organization to tense the belt 24.

In this modification, if relieving force is applied upwardly to the end of arm 90e, as indicated by the arrow 202, then the first action will be to rotate 90e, tube 30, arm 70 and roller 62 to the dotted line positions, that movement being limited by some stop, such as 204. The outer end of 30 does not move up until the stopped rotational position is reached, when further upward pressure at 202 will then raise 30 and 90e translationally, guided by link 102e.

The mechanism of the invention has wide adaptability to various relative locations of the car axle and its wheel or drum from which the drive is taken, and of the shaft which is to be driven. It is saved from unnecessary wear in all of its parts when its operation is not desired on a car in transit. It also is of such a nature that, aside from its shaft journals and similar elements, no particular precision is required in making and assembling the several parts. And the mounting of the mechanism on the car body is very simple, requires no great precision, and allows fully for variations in car designs and dimensions and for changes of configuration under varying stresses.

It will be noted that the entire drive mechanism is directly mounted on the car body at only two points; at the loose or universal pivot on mounting pin 44, and at the swinging link 102. The mounting at pin 44 allows of a substantial variation in the relative positions of the pin and tube 30 in a direction longitudinal of the tube. Although the fixed positioning of the whole mechanism in that direction might be taken care of at that pivot pin, the preferred arrangement is to fix that positioning through link 102.

Link arm 102 is pivotally mounted on stud 106 and has its hub 104 pressed axially against a shoulder by spring 105. The immediate shoulder as shown here is the hub 108 of manipulation lever 109 which in turn is pressed against shoulder 107. Link arm 102 is thus confined against loose movement on the car body in a direction longitudinally of carrier tube 30, and the several parts are held against looseness by the spring 105.

At its swinging end, link 102 has a rubber or similar bushing 101 in its boss end 100, stud 98 passing through the flexible bushing and being confined endwise by shoulder 99 and a pin 97.

The arrangement is such as to confine stud 98, arm 90 and tube 30 in a direction longitudinal of the tube, and at the same time to allow the relative gyratory movements between the tube, arm and stud and the link arm 102 which are necessitated by the described movements of the outer end of the carrier tube. Shaft 28 is, of course, assumed to be fixed longitudinally of tube 30 in which it is journaled.

The relative movements between the car body and the wheel and axle unit which occur in car use and operation are fully provided for. Relative vertical movements due to load changes and vertical spring action merely cause the traction roller 62 to ride higher or lower on the drum (or wheel) 64. Considerable change in that regard causes only a small angular shift of hanger arm 70 and arm 90 about the axis of tube 30. That is the primary reason why it is preferred to have 10 62 contact the side rather than the top of a drum or wheel. Also the drum centered on the axle length is preferred as a driving element to a car wheel because the drum can be made of ample length to prevent roller 62 from running off its end with relative lateral movement between car body and running gear or with swivelling motion of the truck. And in the swivelling motion (which of course takes place about an axis longitudinally removed from the axle and drum) the angular positions of 70 and 90 about the axis of 30 are not greatly changed. The normal spacing of pin 92 from its stop surface (94) is made large enough to fully take care of all angular movements of hanger arm 70, so that in normal operation that arm does not limit the motion of carrier tube 30. It is only when the mechanism is put out of operation, to save it from needless wear when accessory operation on the moving car is not desired or when the accessory is to be driven from another power supply, that pin 92 on arm 90 comes into action as a pivot.

We claim:

1. Driving mechanism for an accessory carried by the body of a car structure which has a running gear element affording a driving drum, the accessory having an operating shaft; said driving mechanism including a driving shaft; shaft carrying structure on which the driving shaft is carried in a position spaced from the accessory shaft in a direction lateral of the driving shaft, said shaft carrying structure including journals carrying the driving shaft near its respective ends, means for mounting one of the journals on the car body for rotation about an axis longitudinal of the driving shaft and for swinging motion, independently of said rotation, about an axis which is transverse of the longitudinal axis and transverse of the direction of the spacing of the two shafts, whereby the other end of the shaft may swing about said transverse axis in directions toward and from the accessory shaft, and including also means for restricting the other one of the journals to movement in directions toward and from the accessory shaft; means for transmitting power from the running gear drum to the first mentioned end of the driving shaft, said transmission means including a transmission element carried by the first mentioned journal in a position eccentric of the longitudinal axis of rotation and being rendered effective by rotation of the said journal about the longitudinal axis in a predetermined actuating direction; a second power transmission acting between the swinging end of the driv-

ing shaft and the accessory shaft and rendered effective by the said swinging movement of that end of the driving shaft in a predetermined actuating direction about said transverse axis; and means tending to rotate the first mentioned journal about the said longitudinal axis in said actuating rotative direction and tending to swing the driving shaft about said transverse axis in said actuating swinging direction.

2. Driving mechanism as defined in claim 1 and including means for causing rotation of the first mentioned journal about the said longitudinal axis in a direction opposite to the said actuating direction and for causing swinging of the driving shaft about the said transverse axis in a direction opposite to the said actuating direction, whereby both said transmissions are rendered ineffective.

3. Driving mechanism as defined in claim 1 and including stop means actuated by virtue of movement of the shaft carrying structure about one of said axes in a direction opposite to the said actuating direction, said stop means establishing upon such actuation a linkage between the two said movements of said structure whereby by continued movement about the said one axis in the last said direction is accompanied by movement about the other axis in a direction opposite to the said actuating direction.

4. Driving mechanism for an accessory carried by the body of a car structure which has a running gear element affording a driving drum, the accessory having an operating shaft; said driving mechanism including a driving shaft, a shaft carrier on which the driving shaft is journaled, means for mounting one end of the shaft carrier on the car body for rotation about an axis longitudinal of the shaft and swinging movement, independently of said rotation, about an axis transverse of the longitudinal axis, a hanger arm affixed to said end of the carrier, a traction roller mounted on the arm and adapted to be moved toward and from the running-gear drum by rotation of the shaft carrier and arm around the longitudinal axis, a transmission by which the driving shaft is driven from the traction roller, means mounting the other end of the shaft carrier on the car body for rotation about said longitudinal axis and for swinging movement about said transverse axis, independent of said rotation, along a line to and from the accessory operating shaft, spring means tending to rotate the carrier about said longitudinal axis in the direction which moves the traction roller toward the drum and tending to move the last mentioned end of the carrier in one direction along its line of movement, and a transmission between the driving and accessory shafts which is rendered effective by movement of the driving shaft in said last mentioned direction.

5. Driving mechanism as defined in claim 4 and in which the means mounting the second mentioned end of the carrier on the car body includes an arm rigidly affixed to said end of the carrier and projecting therefrom transversely, a mounting link pivoted at one end to the car body and at the other end to said arm adjacent the shaft carrier, at least one of the link pivots being loose, the mounting for the first mentioned end of the carrier being an effective point support for that end of the carrier, the rigid arm and its end of the carrier forming a unit, a stop adapted to be engaged by the outer end of said arm upon limited movement of said unit in the direction

that renders the accessory shaft transmission ineffective, and said mechanism also including means, engageable with said unit at a point removed along the length of the arm from its stop engaging end, and adapted to move the unit in said last mentioned direction.

6. Driving mechanism for an accessory carried by the body of a car structure which has a running gear element affording a driving drum, the accessory having an operating shaft; said driving mechanism including a driving shaft, a shaft carrier on which the driving shaft is journaled, means for mounting one end of the shaft carrier on the car body for rotation about an axis longitudinal of the shaft and swinging movement, independently of said rotation, about an axis transverse of the longitudinal axis, a hanger arm affixed to said end of the carrier, a transmission element journaled on the outer end of the hanger arm and adapted to be moved to and from the running-gear drum by rotation of the shaft carrier and arm around the longitudinal axis, said transmission element forming a part of a transmission between the drum and said driving shaft which is rendered effective by rotational movement of the shaft carrier and arm about the longitudinal axis in one direction, means mounting the other end of the shaft carrier on the car body for rotation about said longitudinal axis and for swinging movement about said transverse axis, independent of said rotation, along a line to and from the accessory operating shaft, spring means tending to rotate the carrier about said longitudinal axis in the direction which renders the transmission effective between the drum and the driving shaft and tending to move the last mentioned end of the carrier in one direction along its line of movement, and a transmission between the driving and accessory shafts which is rendered effective by movement of the driving shaft in said last mentioned direction.

7. Driving mechanism as defined in claim 6, and in which the first mentioned mounting means comprises an effective point support for the shaft carrier located on the longitudinal axis of carrier rotation.

8. Driving mechanism as defined in claim 6, and in which the second mentioned mounting means for the second mentioned end of the shaft carrier comprises a link pivotally connected at one end to the car body and at its other end to the shaft carrier, one at least of said pivotal connections allowing relative swinging movement of the carrier about an axis transverse of its longitudinal axis of rotation.

9. Driving mechanism as defined in claim 8 and in which said second mentioned mounting means also comprises an arm rigidly affixed to the second mentioned end of the shaft carrier and projecting therefrom transversely of the carrier's longitudinal axis of rotation, said arm and carrier-end forming a unit which is rotatable with respect to the pivotally connected link, a pivot element forming a part of said unit and adapted to engage a stop surface on the car body upon movement of the unit in a direction which renders the accessory shaft transmission ineffective, and said mechanism also including means, engageable with said unit at a point removed along the length of said arm from the pivot element, and adapted to move the unit in the direction which renders the accessory shaft transmission ineffective.

10. Driving mechanism as defined in claim 6

and also including an arm rigidly affixed to the second mentioned end of the shaft carrier and projecting therefrom transversely of the carrier's longitudinal axis of rotation, said arm and carrier end forming a unit, and a stop limiting movement of the outer end of the arm in the direction in which the carrier moves to render the accessory shaft transmission ineffective.

11. Driving mechanism as defined in claim 10 and also including means, engageable with said carrier-arm unit at a point removed along the length of the arm from its stop engaging end, and adapted to move the unit in the direction which renders the accessory shaft transmission ineffective.

12. Driving mechanism as defined in claim 6 and in which the spring means comprises a single torsion spring element extending longitudinally of the shaft carrier and having a transverse arm at one end, the other end of the torsion spring being connected to the shaft carrier, the transverse arm being connected at its free end with the car body, and the spring element being also connected, at a point near the junction of the transverse arm with the torsion element, with the shaft carrier at a point near its second mentioned end.

13. Driving mechanism as defined in claim 6 and in which the spring means comprises a single torsion spring element which includes a torsion bar extending longitudinally of the shaft carrier and having transverse arms at its opposite ends, one of said transverse arms being connected with the first mentioned end of the shaft carrier, the other of the transverse arms being connected at its free end with the car body, and the spring element being also connected, at a point near the junction of the latter mentioned arm with the torsion bar, with the shaft carrier at a point near its second mentioned end.

14. Driving mechanism as defined in claim 6 and in which the second mentioned mounting means for the second mentioned end of the shaft carrier comprises a arm rigidly affixed to that end of the carrier and projecting therefrom transversely of the carrier's longitudinal axis of rotation, a pivot forming element on the free end of said arm adapted to engage a stop surface on the car body upon movement of the arm with the end of the carrier in the direction which renders the accessory shaft transmission ineffective, and a link pivotally connected at one end to the car body and at its other end to said arm near the carrier, one at least of said pivotal connections allowing relative swinging movement of the carrier about the axis transverse of its longitudinal axis of rotation.

15. Driving mechanism as defined in claim 14, and also including a manually operable lever pivoted on the car body and adapted to be moved against the second mentioned pivotal connection of said link in the direction of movement which renders the accessory shaft transmission inoperative.

16. Driving mechanism as defined in claim 1, and including means for limiting motion of the shaft carrying structure about one of said axes in the direction opposite to the said actuating direction.

17. Driving mechanism as defined in claim 1, and including an arm carried by and projecting transversely from the first mentioned journal, and a stop engageable by the arm by virtue of movement of that journal about the transverse

19

axis in the direction opposite to said actuating direction.

18. Driving mechanism as defined in claim 17, and in which the relation of the arm and the stop to the longitudinal axis of said journal is such that continued movement of the journal about the transverse axis after engagement of the stop by the arm causes rotational movement of the journal about the longitudinal axis in a direction opposite to said actuating direction.

19. Driving mechanism as defined in claim 1, and in which the last mentioned means comprises a single torsion spring element extending longitudinally of the driving shaft and having a transverse arm at one end, the other end of the torsion spring being connected to the first mentioned journal, the transverse arm being connected at its free end to the car body, and the

5

20

spring element being also connected, at a point near the junction of the transverse arm with the torsion element, with the second mentioned journal.
